(57) **CLAIM**

The ornamental design for a probe microscope, as shown and described.

DESCRIPTION

FIG. 1 is a perspective view of a probe microscope. FIG. 2 is a front view of the probe microscope of FIG. 1. FIG. 3 is a rear view of the probe microscope of FIG. 1. FIG. 4 is a left side view of the probe microscope of FIG. 1. FIG. 5 is a right side view of the probe microscope of FIG. 1.

FIG. 6 is a top view of the probe microscope of FIG. 1. FIG. 7 is a bottom view of the probe microscope of FIG. 1. FIG. 8 is a partial enlarged view of FIG. 1; and, FIG. 9 is a partial enlarged view of FIG. 2.

The ornamental design which is claimed is shown in solid lines in the drawings. In the drawings, the broken lines depict environmental subject matter only and form no part of the claimed design. The dot dot dash lines shown as unclaimed lines in FIGS. 1, 2, 8, and 9 indicate enlarged partial views.
